HEDDLE CONSTRUCTION

Howard O. Coddington, Spartanburg, S. C., assignor to Andrews Company, Spartanburg, S. C.

Application July 28, 1938, Serial No. 221,820

2 Claims. (Cl. 139—92)

This invention relates to heddle construction, the primary object of the invention being to provide a combination heddle bar support, lock hook and brace for use in connection with heddle frames.

- An important object of the invention is to provide a support for heddle bars which will maintain the bars in proper spaced relation with each other at all times, thereby insuring against the 10 heddle frame being stretched when fastened by straps in the loom, to the end that the heddles will not bind on their bars, resulting in a free movement of the heddles and a much finer quality of cloth being woven.
- 15 A further object of the combination lock hook and bar support and brace is to make use of old wooden shafts of heddle frames, which are usually discarded after the usual twine harness supported thereon is rendered useless through wear.
- 20 With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

30 Referring to the drawing:

Figure 1 is a fragmental elevational view of a heddle frame equipped with a combination heddle bar support, lock hook and brace constructed in accordance with the invention.

35 Figure 2 is a sectional view taken on line 2—2 of Figure 1.

Figure 3 is a sectional view taken on line 3—3 of Figure 1.

Figure 4 is an enlarged sectional view taken on line 4—4 of Figure 1.

40 Figure 5 is a view illustrating the lock hook and brace prior to positioning on the heddle frame.

Referring to the drawing in detail, the upper 45 and lower bars of a twine heddle frame are indicated generally by the reference character 5, the ends of the bars being connected in the usual and well known manner.

Disposed intermediate the ends of the bars 5 50 are supporting hooks 6, which are formed with threaded extensions 7 adapted to be positioned in the inner edges of the bars 5, as shown by Figure 2 of the drawing.

These supporting hooks have open sides of

widths to accommodate the heddle bars 8 which are of the usual and well known construction, and on which the heddles indicated at 9 are threaded.

The brace bar, forming the important feature of the present invention, is indicated by the reference character 10 and as shown, is formed with cut-out portions extending inwardly from one of the side edges thereof at points adjacent to the ends of the bar, the cut-out portions defining hooks 11, adapted to hook over the heddle bars 8 10 supported therein, to prevent the heddle bars from moving with respect to each other.

Spring clips indicated at 12 are secured to the brace bar 10, at points beyond the outer edges of the heddle bars 8, the spring clips being constructed to grip the supporting hooks 6, in a manner as shown by Figure 2, to the end that the brace bar will be securely held in position at all times, and may only be removed by directing pressure on the clips to overcome the spring action thereof against the supporting hooks 6.

From the foregoing it will be seen that due to the construction shown and described, the heddle bars are held in exact parallel relation with respect to each other at all times, regardless of the 25 pressure brought to bear on the heddle frame, when the frame is fastened by the usual straps in a loom.

I claim:

1. In a heddle frame, upper and lower heddle 30 frame bars, heddle bar hooks extending inwardly from the heddle frame bars, heddle bars held within the heddle bar hooks, a connecting bar between the heddle bars, hooks at the ends of the connecting bar and adapted to hook over the 35 heddle bars at points adjacent to the heddle bar hooks, clips secured to the connecting bar adjacent to the ends thereof, and said clips adapted to grip the heddle bar hooks, securing the connecting bar in position on the heddle bar.

2. In a heddle frame, upper and lower heddle 40 frame bars, heddle bar hooks extending inwardly from the heddle frame bars, heddle bars held within the heddle bar hooks a connecting bar having elongated openings formed adjacent to the ends thereof and having their edges cut away adjacent to the elongated opening providing hooks 45 cooperating with the heddle bar hooks in supporting said heddle bars, and spring clips mounted on the connecting bar and adapted to grip the heddle bar hooks, securing the connecting bar to said heddle bars.

HOWARD O. CODDINGTON.
